CLAIM

The ornamental design for a front bumper for a vehicle as shown and described.

DESCRIPTION

This application contains subject matter related to the following co-pending U.S. design patent applications: Application Ser. No. 29/842,472, filed Jun. 14, 2022 and entitled “FRONT BUMPER FOR a VEHICLE;” and Application Ser. No. 29/885,900, filed Mar. 2, 2023 and entitled “FRONT BUMPER FOR a VEHICLE.”

FIG. 1 is a front view of a front bumper for a vehicle according to the design;

FIG. 2 is a right, front perspective view thereof;

FIG. 3 is a left, bottom perspective view thereof;

FIG. 4 is a right side view thereof;

FIG. 5 is a left side view thereof;

FIG. 6 is a top view thereof;

FIG. 7 is a bottom view thereof; and,

FIG. 8 is a rear view thereof.
